(57) **CLAIM**

The ornamental design for a raceway for cable management, as shown and described.

DESCRIPTION

FIG. 1 is an isometric view of the design for a raceway for cable management, depicted in a horizontal orientation, showing our new invention;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken line showing in the drawing views is included for the purpose of illustrating environment and forms no part of the claimed design.
